UNITED STATES PATENT OFFICE.

GIUSEPPE MALVICA, OF PITTSBURGH, PENNSYLVANIA.

ATTACHMENT FOR STRINGED INSTRUMENTS.

1,404,131.

Specification of Letters Patent. Patented Jan. 17, 1922.

Application filed April 26, 1920. Serial No. 376,827.

To all whom it may concern:

Be it known that I, GIUSEPPE MALVICA, subject of the King of Italy, residing at Pittsburgh, in the county of Allegheny and State of Pennsylvania, have invented new and useful Improvements in Attachments for Stringed Instruments, of which the following is a specification.

This invention relates to attachments for stringed instruments and has for an object the provision of an attachment which may be readily secured to a banjo, mandolin, guitar or the like to vary the tone.

Another object of the invention is the provision of an attachment by means of which the player may increase or diminish the volume of sound by a pressure of the hand used in playing the instrument and thereby add to the expression of the selection played.

Other objects and advantages of the invention will appear as the following description is read in connection with the accompanying drawings.

In the drawings:

Fig. 1 is a plan view of a string instrument with the invention applied thereto.

Fig. 2 is a side elevation of the same.

Fig. 3 is an end view.

Fig. 4 is a section on the line 4—4 of Figure 1.

Fig. 5 is a detailed perspective view of the spring arch.

Figure 6 is a sectional view taken on a line longitudinally of the strings.

Referring in detail to the drawings, wherein like characters of reference denote corresponding parts, there is illustrated a string instrument which includes a head 10, a neck 11 and strings 12, the latter being spaced from the head by means of the usual bridge 13. The foregoing structure is of the usual construction, the invention residing in the provision of a device which is detachably and adjustably secured to the instrument.

This device comprises a member 14 which is preferably formed of spring wire and has its ends bent substantially at right angles for insertion in clamps 15 provided upon opposite sides of the instrument head. The right angular portions of the member 14 are adjustably secured in position by means of set screws 16, so that the intermediate portion of the member, which extends across the banjo head may be adjusted with

respect thereto. The member 14 further includes an offset portion 17 which is curved downwardly and positioned directly over and spaced above the strings between the tail piece and the bridge, so that it may be easily depressed into contact with the strings. By providing the offset curved portion 17, the right angled portions of the member 14 may be of sufficient length to afford greater flexibility and thus increase the effective action of the device. Looped around the offset portion 17 of the member 14 is a flexible member which is formed of any suitable material and whose ends are secured to the instrument head by any desired means; for example, by the fastening device which secures the tail piece to the instrument. This offset portion 17 of the member 14 has a tendency to maintain the loop of the flexible member in proper position.

In the use of the invention, the member 14 is adjusted to its proper position, with the offset portion 17 slightly spaced above the strings 12. In playing the instrument, the wrist or ball of the hand which is used for picking the strings, rests upon the flexible member, the latter being indicated at 18. A slight pressure upon this member 18 will depress the offset portion 17 into contact with the strings to vary the tone of the latter. Thus the device may be used to produce a tremulous or vibrating tone, by alternately pressing the same upon and permitting it to rise from the strings, or it may be held in contact with the strings to soften the tone after the manner of a mute.

The invention is susceptible of various changes in its form, proportions and minor details of construction and the right is here reserved to make such changes as properly fall within the scope of the appended claims.

Having described the invention what is claimed is:

1. The combination with a stringed instrument including a head, of a spring member secured to the rim of the head and extending transversely over the strings and capable of being depressed into contact therewith.

2. The combination with a stringed instrument including a head, of a resilient member secured to the rim of the head and normally extending transversely over the strings, said member comprising vertically

disposed arms and a bar connecting the arms and means for adjustably securing the arms to the rim.

3. The combination with a stringed instrument including a head, of a vertically adjustable spring member secured to the rim of the head and extending over the strings and capable of being depressed into contact therewith.

10 4. The combination with a stringed instrument including a head, of a spring member having each of its ends adjustably secured to the rim of the head and extending over the strings and capable of being depressed into contact therewith and a flexible member extending around the spring member and secured to the rim of the instrument.

5. The combination with a stringed instrument including a head, of a spring member secured to the rim of the head and extending over the strings and capable of being depressed into contact therewith and a hand rest connected to said member and providing means for depressing the same.

20 6. The combination with a stringed instrument including a head, of a spring member secured to the rim of the head and extending over the strings and capable of being depressed into contact therewith and a strip of flexible material passing around said member and secured to said rim to provide a combined hand rest and member depressing means.

30 35 7. The combination with a stringed instrument including a head, of a spring member, said member comprising vertically disposed arms and a bar connecting the arms,

40 sockets located upon opposite sides of the rim of the instrument head for receiving the arms, means for adjustably holding the arms within the sockets, whereby the bar will be positioned transversely over and spaced above the strings in a manner to permit of said bar being depressed into contact 45 with the strings to vary the tone.

8. The combination with a stringed instrument including a head, of a spring member secured to the head and extending over the strings and capable of being depressed 50 into contact therewith and a hand rest connected to said member and providing means for depressing the same.

9. The combination with a stringed instrument including a head, of a spring member secured to the head and extending over the strings and capable of being depressed 55 into contact therewith and a strip of flexible material passing around the member and secured to said head to provide a combined 60 hand rest and member depressing means.

10. The combination with a stringed instrument including a head, of a spring member, said member comprising vertically disposed arms and a bar connecting the arms, 65 sockets located upon opposite sides of the instrument head for receiving the arms, means for adjustably holding the arms within the sockets, whereby the bar will be positioned transversely over and spaced above 70 the strings of the instrument in a manner to permit of its being depressed into contact therewith to vary the tone.

In testimony whereof I affix my signature.

GIUSEPPE MALVICA.
